UNITED STATES PATENT OFFICE

2,378,361

APPARATUS FOR CLEANING TEXTILE MACHINES

Carroll de V. Miller, Rocky River, Ohio, assignor to The American Monorail Company, Cleveland, Ohio, a corporation of Ohio

Application October 9, 1944, Serial No. 557,783

13 Claims. (Cl. 230—270)

This invention relates generally to the art of cleaning textile machinery and the like and relates more particularly to blowing apparatus which may be controlled so as effectively to clean operating textile machines and so as not to affect harmfully the roving and the like on idle textile machines.

In the Lawrence and Zekely Patent No. 2,175,608 of October 10, 1939, is shown blowing apparatus which travels over rows of textile machines and discharges a stream of air downwardly upon the machines in such a manner that they are kept free from harmful accumulations of dust, lint and the like.

The blowing apparatus of that patent includes a fan which rotates within a housing and blows air downwardly as the fan moves along a track disposed above and extending lengthwise of a row of aligned textile machines. Frequently one or more of the textile machines in such a row, such as spinning frames, are shut down temporarily either to suit the production schedule of the mill or for setting the machine or making repairs thereon. Since the stream of air from the blower may be moving at a velocity sufficiently high to disturb seriously the roving on an idle machine, it is desirable that such disturbances of the roving should be avoided. Yet at the same time sufficient air velocity should be maintained to prevent accumulation of dust and lint on the idle machine.

In the Lawrence U. S. Patent No. 2,291,598, issued August 4, 1942, is disclosed one means of preventing such disturbance of the roving on an idle spinning frame. According to that patent the passages, thru which air is taken into the housing surrounding the rotating fan, are substantially closed when the blower approaches an idle spinning frame and are opened as the blower moves beyond an idle frame or frames and approaches an operating frame. The closing of the air intake passages reduces the air discharged by the blower onto the idle frame or frames there-beneath and minimizes or avoids the disturbances of the roving.

The present invention solves the problem in a new and different manner and by new and improved apparatus and a new and improved mode of operation. This invention is based on the use of the fan rotating means to change quickly the rotational speed of the fan from one speed to another while continuing the rotation of the fan.

In the drawings accompanying and forming a part of this specification,

Figure 1 is a somewhat schematic, fragmentary,

side elevational view of one embodiment of the present invention as applied to a plurality of spinning frames; and,

Figure 2 is an end elevational view, partly in section, taken on line 2—2 of Fig. 1.

In Fig. 1 a plurality of spinning frames 1 are arranged end-to-end in a row. An overhead conveyor 2 extends lengthwise of the frame 1 and centrally thereabove, and is suspended from suitable overhead supports (not shown) by rods 3. The blower illustrated comprises a tubular housing 4 which is open at the bottom, has intake openings 5 in its vertical side walls and has an upper closed end with a fan-rotating motor 6 disposed above the closed end of the housing and a fan 7 within the housing connected to the rotor shaft 8 of the motor 6. The housing 4, motor 6 and fan 7 are suspended by brackets 9 attached to the upper end of the housing 4 and a rod 10 which depends from a trolley frame 11 and engages with brackets 9. Trolley wheels 12 arranged in pairs to run on the outwardly projecting flanges of rail 2 are mounted in trolley brackets 13 which have swiveled connections with frame 11 and serve to support the latter and the housing and other parts just enumerated thru rod 10 and brackets 9.

The frame 11 supports a rotatable shaft on which is mounted a wheel preferably including a pneumatic tire, the periphery of which bears against the under surface of the rail 2. This wheel is rotated by means of a motor 15 thru inter-engaging gears 16 and 17 on the motor and wheel shaft respectively. Obviously any other suitable and well known means may be employed for transmitting rotational movement from the rotor of motor 15 to the shaft of wheel 14.

The motor 15 is connected to a source of actuating current by means of collectors 18 which are carried by arms extending upwardly from the brackets 13 and which have sliding engagement with conductors 19 supported by the hanger rods 3 and connected to a suitable source of electrical current.

It will be understood from the foregoing that when current is supplied to the conductors 19 the motor 15 will actuate wheel 14 and thereby will cause the frame 11 and the blower attached thereto to move at a constant speed along the track 2 above the spinning frame 1.

Conductors connected to collectors 18 supply the fan motor 6 with actuating current thru a switch 21 mounted on the blower housing 4. This switch may be of the star wheel type, that is, it may be provided with a wheel, such as 22, which has a plurality of radial fingers and which is se-

cured to a shaft 24 which, when rotated by the star wheel, will actuate the switch 18.

The motor 6 is preferably of the 2-speed, squirrel cage, induction, two-winding type, one full load speed being preferably about 1750 R. P. M. and the other preferably about 850 R. P. M. It will be understood by those skilled in the art that such full load speeds of induction motors correspond to synchronous speeds of 1800 and 900 R. P. M. respectively to which such motors tend to approach under no load conditions. The switch 21 is accordingly provided with a pair of stationary switching elements for each of these speeds and the star wheel shaft 24 is also provided with switching elements which may be brought alternately into connection with these fixed switching elements so that when the star wheel 22 is actuated thru one step current will be supplied to the set of windings on the motor which will result in the rotor rotating at a speed of about 1750 R. P. M. and when the star wheel is rotated another step those connections will be broken and connections will be made between the source of current and the other set of windings which will result in rotating the rotor of motor 6 at a speed of about 900 R. P. M. The next actuation of the star wheel thru one step will disconnect the low speed windings and connect the high speed windings with the source of current, thereby increasing the speed of the rotor of motor 6.

Means for actuating the star wheel 22 thru one step, as just described, is shown in Figs. 1 and 2. This means, illustrated, includes an arm 25 which at one end may be supported by a rail hanger 26 projecting upwardly from between the assembled halves of the rail 2, and which extends horizontally out from hanger 26 to a point beyond the motor 15 and then projects downwardly to a point just above the star wheel 22. At its lower end the arm 25 pivotally supports a lever 27 which is disposed directly above the star wheel 22 and is kept out of engagement with that wheel by any suitable means such as coil spring 28. A rope or cable 29 is attached to one end of lever 27 and is threaded over a pulley wheel 30 supported above and at one side of the rail 2 so as to clear the side of the blower.

One of the star wheel actuating units just described may be permanently installed at the trailing end of each spinning frame, that is, the trailing end of the frame considering the direction of the movement of the blower thereover; or, two of these units may be readily installed, one in advance of the leading end and the other near the trailing end of a spinning frame when the latter is idle or is to cease operation. Obviously two of such units will suffice when two or more consecutively positioned machines are to be idle simultaneously.

The mode of operation of the hereinbefore described apparatus is substantially as follows: Assuming that the middle frame on Fig. 1 is idle while the end frames are operating, and that the blower is moving along track 2 in the direction of the arrow with the fan motor rotating at about 1750 R. P. M., the free ends of the ropes or cables 29 of the star wheel actuating units are pulled so that the spring 28 is stretched and the spring-engaged ends of levers 27 are moved downwardly far enough to engage a radial arm on the star wheel 22 when the latter passes therebeneath, and the ropes are then secured to hold the levers in that position. Under these conditions one arm of the star wheel 22 will engage the first or left-

hand lever 27 as the blower moves past the latter and the star wheel will be rotated thru about 60 degrees, shifting the switching members in switch 21 so as to disconnect the source of current from the high speed windings and to connect the source of current with the low speed windings of the motor. By the time the blower has reached the leading end of the middle, idle frame 1, the rotational speed of the motor rotor will be about 900 R. P. M. due to the inherent braking characteristics of the motor when the rotor is rotating at a speed above the lower synchronous speed. The rotor will thereafter fall in speed to 850 R. P. M. owing to being loaded by the blower fan after the inertia energy has been dissipated by the braking effect, and the rotor will continue to rotate at that speed until the second or righthand lever 27 engages another arm on the star wheel and rotates it thru about 60 degrees, thereby interrupting the flow of current to the low speed windings of the motor 6 and connecting the current with the high speed windings of the motor. Thereupon the rotational speed of the motor rotor increases quickly so that by the time the blower reaches the near end of the righthand frame which is operating, the rotational speed of the rotor will be about 1750 R. P. M. In this manner the fan is operated continuously but its speed is automatically increased when the blower leaves an idle machine and approaches an operating machine, such speed being sufficient to blow enough air, or air at a high enough velocity to remove dust, lint and the like from the operating machine and is automatically braked and decreased when the blower leaves an operating machine and approaches an idle machine to such an extent that the stream of air from the blower will not be sufficiently great in amount or velocity to seriously disturb the roving on the idle spinning frame but will be sufficient to agitate lint in the air and tend to prevent it from settling on the idle machine.

This application is a continuation-in-part of my copending application Ser. No. 470,457, filed December 29, 1942.

Altho I prefer to use a squirrel cage, induction, two-winding motor to rotate the fan, other types of braking motors may be used if desired. For example, I may use an A. C. motor having one winding and a pole changing controller or contactor, or a dual synchronous motor, or two motors of different speeds connected to the same fan shaft with power applied alternately to these motors.

Having thus described my invention so that others skilled in the art may be able to understand and practice the same, I state that what I desire to secure by Letters Patent is defined in what is claimed.

What is claimed is:

1. Apparatus of the class described comprising a track extending lengthwise of and above a line of textile machines arranged in a row, a blower to run along said track and to blow air down onto said machines, electrical multi-speed motor means of the type serving as a brake in the lower speed setting when driven above its lower speed operatively connected to the blower for actuating said blower at different speeds, and means for changing the speed of said motor means from one to another of said speeds.

2. Apparatus of the class described comprising a track extending lengthwise of and above a line of textile machines arranged in a row, a blower to run along said track and to blow air down onto

said machines, and electrical, multi-speed motor means operatively connected to said blower to actuate the latter at different speeds, said motor means being of the braking type and serving automatically to reduce the speed of the blower when the speed of the motor means is changed to a lower speed.

3. Apparatus of the class described comprising a track extending lengthwise of and above a line of textile machines arranged in a row, a fan to run along said track and to blow air down onto said machines, a multi-speed alternating current motor having a rotor operatively connected to said fan to actuate the latter, the motor being of the type having a synchronous speed in each speed setting which it tends to approach in operation, and means for energizing said motor to actuate said rotor at any one of at least two different speeds.

4. Apparatus of the class described comprising a track extending lengthwise of and above a line of textile machines arranged in a row, a fan to run along said track and to blow air down onto said machines, a multi-speed alternating current motor having a rotor operatively connected to said fan to actuate the latter, the motor being of the type having a synchronous speed in each speed setting which it tends to approach in operation, current conducting means for energizing said motor, and means for changing the rotational speed of said rotor from one speed to another of the speeds of said motor.

5. Apparatus of the class described comprising a track extending lengthwise of and above a line of textile machines arranged in a row, a fan to run along said track and to blow air down onto said machines, a squirrel cage, induction type, alternating current motor having a rotor operatively connected to said fan to actuate the latter and having two separate windings for two different rotational speeds of the rotor, current conducting means for energizing one or the other of said windings, and a switch movable with said motor for connecting said current conducting means with one or the other of said windings.

6. Apparatus of the class described comprising a track extending lengthwise of and above a line of textile machines arranged in a row, a fan to run along said track and to blow air down onto said machines, a squirrel cage, induction type, alternating current motor having a rotor operatively connected to said fan to actuate the latter and having two separate windings for two different rotational speeds of the rotor, current conducting means for energizing one or the other of said windings, a switch movable with said motor for connecting said current conducting means with one or the other of said windings, and means at predetermined points along said track for actuating said switch as it moves therewith.

7. Apparatus of the class described comprising a track extending lengthwise of and above a line of textile machines arranged in a row, a fan to run along said track and to blow air down onto said machines, an alternating current motor having a rotor operatively connected to said fan to actuate the latter and having one winding and a pole changer for rotation of the rotor at two different rotational speeds, and means for actuating said pole changer and thereby changing the rotation-

al speed of said rotor from one speed to another speed.

8. Apparatus of the class described comprising a track extending lengthwise of and above a line of textile machines arranged in a row, a blower adapted to run along a track above a line of textile machines and to blow air downwardly onto said machines, said blower comprising a fan, a dual synchronous, alternating current motor having a rotor operatively connected to said fan to rotate the latter at different rotational speeds, and means for connecting a source of alternating current with said motor to actuate the rotor thereof at one or the other of its two synchronous speeds.

9. Apparatus of the class described comprising a track extending lengthwise of and above a line of textile machines arranged in a row, a fan to run along said track and to blow air down onto said machines, a dual synchronous, alternating current motor having a rotor operatively connected to said fan to rotate the latter at different rotational speeds, and means for connecting a source of alternating current with said motor to actuate the rotor thereof at one or the other of its synchronous speeds.

10. A blower adapted to run along a track above a line of textile machines and to blow air downwardly onto said machines, said blower comprising a fan having a vertical shaft, electrical multi-speed motor means of the type inherently braking when driven above its lower speed, operatively connected to said shaft for rotating the shaft and fan at different speeds, and means for actuating said motor means to rotate said shaft and fan at one or another of the different speeds of said motor means.

11. A blower adapted to run along a track above a line of textile machines and to blow air downwardly onto said machines, said blower comprising a fan having a vertical shaft, a squirrel cage, induction type, alternating current motor having a rotor operatively connected to said fan shaft and having a plurality of separate windings for actuation of the rotor at different rotational speeds, means for connecting a source of alternating current selectively with one or another of said windings, and means for actuating said connecting means.

12. A blower adapted to run on a track above a line of textile machines and to blow air downwardly onto said machines, said blower comprising a fan having a vertical shaft, an alternating current motor having a rotor operatively connected to said shaft and having one winding and a pole changer, means for connecting a source of alternating current with said winding, and means for actuating said pole changer.

13. A blower adapted to run along a track above a line of textile machines and to blow air downwardly onto said machines, said blower comprising a fan having a vertical shaft, a dual synchronous, alternating current motor having a rotor operatively connected to said shaft, means for connecting a source of alternating current to said motor, and means for changing the speed of said rotor from one to the other of the two synchronous speeds of the motor.
